UNITED STATES PATENT OFFICE.

FRANK W. WATERMAN, OF BALTIMORE, MARYLAND, ASSIGNOR TO THE
WATERMAN SPRING BOTTLE SEAL COMPANY, OF SAME PLACE.

BOTTLE-STOPPER.

SPECIFICATION forming part of Letters Patent No. 617,975, dated January 17, 1899.

Application filed February 8, 1897. Serial No. 622,505. (No model.)

To all whom it may concern:

Be it known that I, FRANK W. WATERMAN, a citizen of the United States, residing at Baltimore, in the State of Maryland, have invented 5
certain new and useful Improvements in
Bottle-Stoppers, of which the following is a
full, clear, and exact specification.

This invention relates to the bottle-stopper
for which Letters Patent No. 568,286 were
issued September 22, 1896.

The chief object of the present invention
is to improve the construction of the spring
clip or fastener, whereby the stopper can be
removed from the mouth of the bottle by the
pressure of a finger without the use of a tool
especially designed for the purpose.

The invention also has for its object to im-
prove the construction of the stopper-cap
itself, whereby it can be more conveniently
and economically manufactured.

These objects are accomplished in the man-
ner and by the means hereinafter described
and claimed, reference being made to the ac-
companying drawings, in which—

Figure 1 is a perspective view showing the
improved stopper and the upper end of a bot-
tle preparatory to forcing the stopper upon
the bottle-mouth. Fig. 2 is a similar view
showing the stopper secured on the bottle-
mouth. Fig. 3 is a side elevation showing
the stopper-cap in section. Fig. 4 is a detail
perspective view of the spring clip or fastener
removed from the bottle-cap. Fig. 5 is a de-
tail perspective view of the cap.

In order to enable those skilled in the art
to make and use my invention, I will now de-
scribe the same in detail, referring to the
drawings, wherein the numeral 1 indicates
the neck of a bottle having an annular groove

2 in juxtaposition to the edge 3 of the bottle-
mouth, this groove serving to create an an-
nular shoulder 4 on the exterior of the mouth
portion of the bottle. The stopper-cap 5 is
in the form of a cup-shaped piece of metal,
45 containing a disk of cork or other suitable
material resting against the inner side of the
top of the cap, so that when the latter is ap-
plied to the bottle-mouth the disk will effec-
tually seal the bottle. The pendent rim 8 of
50 the cap is provided at opposite sides with
elongated notches 9 and 9^a cut directly in the

lower edge of the cap in contradistinction to
slots cut in the rim considerably above the
lower edge of the cap-rim, as in the former
patent.

55

The spring clip or fastener, by which the
cap is removably secured in an effectual man-
ner upon the bottle-mouth, is composed of a
single piece of wire bent to form two sepa-
rated members 10, which lie over the top of 60
the cap, and two separated hook-shaped ex-
tremities 12, the two members 10 of the wire
opposite the hook-shaped extremities being
bent, as at 13, toward each other and slightly
toward the hook-shaped extremities, and 65
thence downward into a loop-shaped finger-
piece 14, which stands in an inclined position
relatively to the horizontal members or por-
tions 10 of the wire, which lie upon the top
of the cap. The hook-shaped extremities 12 70
project toward the loop-shaped finger-piece,
and extend through the notch 9^a, while the
bent portions 13 extend through the notch 9
in a direction toward hook-shaped extremi-
ties, the construction being such that the 75
spring clip or fastener is connected with the
cap without liability of separation, and if the
cap be pressed down upon the bottle-mouth
the hook-shaped extremities 12 and the bent
portions 13 will yield outward as they pass 80
the annular shoulder 4 and then spring into
the annular groove to firmly engage the lower
side of the annular shoulder. By this means
the stopper will be securely held upon the
bottle-mouth and the latter will be sealed; 85
but whenever it is desired to open the bottle
it is only essential to place a finger of the
hand under or otherwise use a finger or fin-
gers of the hand to raise the fastener and cap
from the bottle.

90

While the spring clip or fastener is con-
nected with the stopper-cap, it is not in any
manner attached permanently to the bottle
neck or mouth, and therefore the entire stop-
per is moved from the bottle when the loop- 95
shaped finger-piece is acted upon to open the
bottle-mouth.

The construction of the sheet-metal stop-
per-cap 5 with the notches 9 and 9^a cut di-
rectly in the lower edge of its pendent rim 100
is a desirable improvement in that the cap
can be made by one passage through a simple

machine constructed to cut the notches and subsequently turn down the rim, which cannot be done where slots are required to be cut in the rim, as in the former patent. The new 5 form of cap is also desirable in that it is exactly alike or uniform at both sides, it requires less material, there is less trouble in fastening the spring-clip, and all parts of the stopper can be assembled in a suitable machine ready for application to a bottle. The 10 notches cut in the lower edge of the pendent rim of the cap also act as guides to place the cap in proper position relatively to the members of the spring-clip.

15 Having thus described my invention, what I claim is—

The combination with a bottle having an external annular groove in its mouth portion, of a sheet-metal cap having a pendent rim

20 with opposite recesses cut directly in its lower edge, and an elastic wire bent to form two separated members lying over the top of the cap and having hooked extremities extending through one of said recesses into the annular groove, said two wire members having, at 25 points opposite the hooked extremities, the portions 13 projecting toward each other into the annular groove through the other recess in the rim and, respectively, bent down into the offsetting depending finger-piece 14, substantially as and for the purposes described. 30

In testimony whereof I have hereunto affixed my signature in the presence of two subscribing witnesses.

FRANK W. WATERMAN.
